UNITED STATES PATENT OFFICE.

SAMUEL CLELAND DAVIDSON, OF BELFAST, IRELAND.

VENTILATION.

1,234,736.

Specification of Letters Patent. Patented July 31, 1917.

Application filed May 11, 1915. Serial No. 27,292.

To all whom it may concern:

Be it known that I, SAMUEL CLELAND DAVIDSON, subject of the King of Great Britain, of Sirocco Engineering Works, Belfast, 5 Ireland, merchant, have invented certain new and useful Improvements Relating to Ventilation, of which the following is a specification.

This invention relates to ventilation and 10 has for its object to provide an improved apparatus for the better ventilation of public buildings, hospitals, ships, and so forth, and is adapted to be placed in convenient positions and connected to a system of air 15 trunks which distribute the air to the required spaces in the usual manner.

According to this invention the apparatus 20 which may combine as a complete unit means for heating, humidifying, ozonizing, and distributing air, is provided with means for breaking the well known monotony of atmosphere usually produced by a plenum system, this being accomplished by providing an automatic device for cutting out 25 or by-passing the heater and turning it on again at certain predetermined intervals.

The automatic control of the heater may 30 be effected by a timed valve driven by gearing from the fan motor or other motor in the apparatus and adapted to turn "on" and "off" the supply of steam to the heater, the frequency with which the heating element is "on" and "off" can be preadjusted so as to produce as near as possible a result which 35 may be likened to the reviving and refreshing effect produced by opening windows in a stuffy room on a breezy day.

As an alternative, the heater may be bypassed by means of a swing damper or similar 40 means operated by gearing from a motor in the apparatus, which damper would cut out the heater and admit cold air from the atmosphere or from an air cooler as the circumstances may require or admit.

45 Where electric heating is used the cut-out arrangement could be arranged to work directly on to a make and break switch or in other suitable manner.

Where steam heat is used each unit preferably 50 consists of a heater of the tubular steam type arranged with one or more sections and which is supplied with steam to the inside of the tube, the air being drawn from the atmosphere over the outside of said 55 tube by means of a centrifugal fan with directly coupled motor and thereby heated

to the required temperature. Another system of heating may be adopted by using an electric heater in which a primary heater is utilized to produce the heat which will 60 then be dissipated through cast iron or similar grids.

Means may also be provided for humidifying the air by the use of a humidifier placed 65 preferably in the fan discharge, the control of the same being interlocked with the main steam supply whereby it is cut off at corresponding periods with the heater.

The combined apparatus may also include means for ozonizing the air by use of a 70 known apparatus consisting of a static transformer and ozone generator, which is placed preferably on the suction side of the fan and in the path of the air. In cases where the air supply is dusty the ozone generator is 75 inclosed and fitted with a filtering medium on the inlet to prevent the clogging of the generator.

In addition to the well known benefits 80 obtained by having the air ozonized, additional advantages are obtained as it has been found that a much smaller volume of ozonized air will give adequate ventilation. Advantages may be taken of this feature to 85 cut down the size of air distributing ducts, which is an important consideration, particularly when applied to ship work where the space available for such ducts is limited.

The accompanying drawings show one 90 construction of heater unit made in accordance with this invention.

Figure 1 is a sectional elevation of the main portion of the apparatus:

Fig. 2 is an end view with part of the 95 casing removed.

Fig. 3 is an end view.

Fig. 4 is a plan.

Fig. 5 is a sectional detail view of the 100 humidifier shown in Fig. 1, and

Figs. 6 and 7 are longitudinal cross sections respectively of the timing valves, and

Fig. 8 is a sectional elevation similar to Fig. 1 showing a modified construction where the heater is by-passed.

Referring to the accompanying drawings 105 Figs. 1 to 7:

a represents a centrifugal fan direct driven by the A. C. electric motor *b*. The air is drawn from the atmosphere through the opening *c* by means of the fan action, 110 and in its path passes over the tubes of the steam heater *d* which may be in one or more

sections. e represents the static transformer which is supplied at the primary with low tension A. C. current and delivers from the secondary high tension A. C. current to the ozone generator f which is situated in the path of the air on its way to fan suction. g represents a baffle plate which partially divides the unit in its height and prevents direct radiation from the heater pipes on to the motor. The whole unit is inclosed by a steel case represented by h and which is lagged with non-conducting material j held in place by sheets k , l represents the steam supply pipe which is connected to the time valve m . This valve is operated by the spindle n through the reduction gear o . The details of the valve m are shown in Figs. 6 and 7 from which it will be seen that the port m' which leads into the rotary plug m^2 travels around for the greater part through the surrounding open passageway m^3 , the passage being cut off on reaching the part m^4 where it makes for a predetermined period a close contact with the inclosing casing and shuts off the supply of steam. The whole of this gear can be placed inside the casing by altering the design and fitting the valves with long handles to be operated from the outside. The reduction gear o is in turn directly driven from the spindle of the fan motor b . p represents valves controlling the heater sections and q represents a valve controlling the steam supply to humidifier. r represents the start of the air duct system. s represents the humidifier which is shown in larger detail in Fig. 5. This humidifier consists of a casing s having a dividing partition t extending to near the bottom; the top is flanged and jointed to a cover u . Steam is admitted to the casting s through the pipe t' which is controlled by the valve q and impinges on the partition t thus depositing any water which may be present, which water is drained away through the pipe v and joins the main drain from the heater. The steam then leaves the humidifier through the comparatively larger bore pipe w which is made with a flared end in order to reduce the velocity. Fig. 8 shows a modified arrangement where the heater is by-passed, in this construction the timing spindle n instead of operating a valve to cut off steam from the heater as in Fig. 1, serves to operate a by-pass flap x through links x' x^2 and bevel wheels y y' . The bevel wheel y' is provided with a pin y^2 working in a slot y^3 in the link y . The by-pass flap x is pivotally mounted about the inlet c to the heater chamber and controls both the inlet c and another inlet c' to a by-pass passage z which passes around to the side of the casing and enters the same below the heater and above the ozonizing apparatus and adjacent to the space which leads to the fan intake. In

operation the flap x first normally occupies the vertical position, closing the duct z and allowing the air to pass in over the heater as indicated by the dotted arrows, while the timing apparatus serves at the predetermined period to lower the flap x and close the inlet c and opening the inlet c' to the by-pass passage z permitting air to pass to the fan without passing over the heater.

What I claim and desire to secure by Letters Patent is:—

1. The combination with a heating and ventilating apparatus of means for continuously supplying air to the structure to be ventilated and automatically acting means for varying the temperature of the air distributed over certain predetermined periods or at prearranged intervals for the purpose of varying the monotony of atmosphere in the ventilated rooms or spaces. 85

2. A combined heating or ventilating and air distributing unit consisting of a heater, an air distributing fan with motor adapted to continuously pass a current of air through the apparatus, and means operated by the motor and adapted to suspend the heating effect of the heater on the air passing through the apparatus. 90

3. A combined heating or ventilating and air distributing unit consisting of a heater, 95 a fan adapted to pass a current of air through the apparatus, a motor driving said fan, and a supply valve driven from the motor and adapted to cut off and turn on the supply of steam or heating medium to 100 the heater at prearranged intervals of time.

4. A combined heating or ventilating and air distributing unit consisting of a casing, 105 an air inlet to the upper part of the casing, an air heater disposed adjacent to the air inlet, a centrifugal fan disposed in the lower part of the casing, a motor driving said fan also disposed in the casing, a shield directing the heated air toward the fan intake, said shield extending over and protecting the 110 motor or a part thereof from the hot air, a discharge duct leading out of the casing from the fan, a valve adapted to cut off and turn on the supply of heating medium to the heater, and an operating connection to said 115 valve from said motor for operating said valve at prearranged intervals of time to cut off and turn on the supply of heating medium to the heater.

5. A combined heating or ventilating and 120 air distributing unit consisting of a casing, an air inlet to the casing, an air heater disposed adjacent to the air inlet, a centrifugal fan disposed in the casing, a motor driving said fan also disposed in the casing, a shield directing the heated air toward the fan intake, said shield extending over and protecting the motor or a part thereof, a discharge duct leading out of the casing from the fan, a valve adapted to cut off and 130

turn on the supply of heating medium to the heater, means including timing gear for operating said valve from the fan motor whereby the valve will be opened and closed at prearranged intervals of time to cut off and turn on the supply of heating medium to the heater.

6. The combination with a heating and ventilating apparatus or unit, of means for continuously supplying air to the structure to be ventilated, a heater adapted to heat said air and automatically operating means for cutting out the heater at predetermined

intervals to vary the temperature of the air distributed over certain periods or at pre-
arranged intervals for the purpose of vary-
ing the monotony of atmosphere in the ven-
tilated rooms or spaces. 15

In witness whereof, I have hereunto signed my name in the presence of two subscrib- 20
ing witnesses.

SAMUEL CLELAND DAVIDSON.
